CLAIM

The ornamental design for a bark control collar device, as shown and described.

DESCRIPTION

FIG. 1 is a perspective view of a bark control collar device showing my new design.

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

Any shading and cross-hatching are not features of the design but are utilized to illustrate the surface contours of the bark control collar device.
